UNITED STATES PATENT OFFICE.

FREDERICK W. STONE, OF MONTREAL, QUEBEC, CANADA, ASSIGNOR TO CENTRAL COMMERCIAL COMPANY, A CORPORATION OF ILLINOIS.

SOUND RECORD.

No Drawing.

Application filed March 31, 1923. Serial No. 629,220.

- The invention relates to records such as are used in phonographs, and like instruments, for the reproduction of sound, and which are formed of plastic material.
- 5 The objects of the invention are to secure a superior smoothness of the material whereby the quality of the sound reproduced is improved, as well as the durability both of the record impressed upon the plate and the 10 needles or points used in connection therewith; and to render the plate less frangible and less liable to warping than it has heretofore been possible to attain.

Plate records have been made of various 15 materials mixed together as a plastic mass and wrought into the desired plate form under pressure, the record being imprinted in the surface or surfaces in this process.

The materials employed have consisted 20 usually of a granular filler constituting the principal ingredient, in quantity, a bonding agent, such as shellac, a coloring element, such as lamp black, and a material such as resin for rendering the surface glossy. In 25 some instances, also, an ingredient of high specific gravity is added to increase the weight of the plate. Sometimes a fibrous material is added. The formulae for these record plates have been quite numerous, and 30 ingredients of somewhat different character than those enumerated have been used.

The sound records heretofore in use have lacked smoothness of texture, with the result that the reproduction of the sounds, 35 whether of speech or music, has been more or less raspy, and the friction, by the movement of the needle or point over the indented surface, has resulted in a too rapid wearing of both parts, necessitating frequent changes of needles and resulting in the rapid deterioration of the impressed record.

The improved record forming the subject 40 of this application is formed of a plastic, of which the filler is finely pulverized slate, preferably of extreme fineness, combined or mixed with any suitable bonding material, such as shellac, and with which may be used any other ingredients, as, for obtaining a desired color, finish or weight. A fibrous material, such as flock, may be added,

if desired, though I have found it quite feasible to omit such an element.

The smoothness of the improved record varies with the degree of fineness of the filler, the best results being obtained by the use of slate reduced to what is sometimes known as "air float" fineness, that is to say, to the form of an impalpable powder which, being diffused in the air, will float for a 55 considerable time. Pulverized slate of a fineness known as 200 mesh, while less desirable, will result in a record superior in smoothness to any now being manufactured, and will have the added advantages of less 60 liability to fracture or warp than has heretofore been secured.

Slate is usually found either green or red in color. Either variety may be used, and may be employed without the use of a coloring material, or such a material may be employed according to the taste of the manufacturer or user.

The specific gravity of the slate is such that plates of which it forms the major ingredient, as to quantity, will have the average weight which at the present time appears to be preferred, rendering it unnecessary to add an ingredient of greater weight.

The present invention is not concerned 75 with the particular character of any of the ingredients except the filler of pulverized slate. It is, of course, essential that there be present a suitable bonding agent, such as shellac, and other ingredients may be added, 80 as for securing any desired surface finish, as preferred.

The improved record has the further advantage of cheapness of manufacture, inasmuch as the filler is less expensive than materials heretofore used for this purpose, and the slate particles may be firmly united by the use of a smaller quantity of binding material than it has heretofore been found necessary to use, thereby further reducing the 85 cost of manufacture.

I claim as my invention—

A sound record comprising in its composition a filler of pulverized slate reduced to a powder of air float fineness, and a suitable 90 bonding material.

FREDERICK W. STONE.
